UNITED STATES PATENT OFFICE.

STEPHEN M. CHESTER, OF ELIZABETH, NEW JERSEY, ASSIGNOR TO
CLAYTON ROCKHILL, OF NEW YORK, N. Y.

APPARATUS FOR WAXING PAPER AND OTHER MATERIAL.

SPECIFICATION forming part of Letters Patent No. 360,373, dated March 29, 1887.

Application filed November 2, 1886. Serial No. 217,823. (No model.)

To all whom it may concern:

Be it known that I, STEPHEN M. CHESTER, of Elizabeth, in the county of Union and State of New Jersey, have invented certain new and useful Improvements in Apparatus for Waxing Paper and other Material; and I do hereby declare the following to be a full, clear, and exact description of the invention, such as will enable others skilled in the art to which it appertains to make and use the same.

My invention relates to an improvement in apparatus for waxing paper and other material.

The object is to provide simple and convenient means for impregnating paper and other material with wax and giving its surface a glossy finished appearance without the employment of stripping-pads and calendering rolls or surfaces, commonly employed for the purpose.

A further object is to provide means for conducting the vapor of the volatile solvent in which the wax is dissolved to a condenser.

With these ends in view my invention consists in certain features of construction and combinations of parts, as will be hereinafter described, and pointed out in the claims.

In the accompanying drawings, Figure 1 is a vertical longitudinal section of the apparatus with parts in adjustment as in use. Fig. 2 is a similar view with cover elevated out of contact with tank, and Fig. 3 is a plan view with top of cover removed. Figs. 4, 5, 6, and 7 represent, respectively, a vertical, longitudinal, and cross section of a modification.

A represents the body of a main tank, preferably elongated, as shown. A second or inner tank, B, narrower and shorter than the tank A, is adapted to be set within the tank A with its top flush with the top of the tank A and leaving a narrow space, a, between the sides and one end of the tank B and the corresponding part of the tank A, and quite a wide space, b, between the remaining end of the tank B and the corresponding end of the tank A. The spaces a and b form one continuous space around the inner tank between its walls and those of the outer tank, and are adapted to be filled with water or other cooling-liquid.

The interior of the inner tank, B, is separated into two compartments, C and C', by means of a cross-partition, D, preferably located nearer one of the ends of the tank than the other; and within the smaller compartment, C', the receptacle E, for holding the supply of dissolved wax, is located.

Along one or both sides of the inner tank, B, near the inner faces of its side walls, the steam or hot-air pipes F extend, which serve to keep the wax solution at the proper temperature, and also keep the compartment C warmed.

G represents the cover, provided with sides and one end sufficiently high to rest on the bottom of the main tank A when its top is at the top of the tank, but having the end g of less height than the sides and opposite end, in order to allow the paper or other material to be waxed to pass between it and the bottom of the tank. The cover G is made of such width and length that its sides and ends will occupy about the middle portion of the spaces a and b when it is lowered into position in the tank A. When in such position, the joints between it and the main tank become hermetically sealed by the water which occupies the spaces a and b. The cover G is provided with several pairs of depending hangers or brackets, H h h' h'', &c., in the present instance four, located, as shown, along the sides of and within the walls of the cover and having the paper-roll spindle K and guide-rollers k k' k'', &c., journaled in their lower ends.

The spindle K, on which the roll of paper or other material L is mounted, is conveniently inserted in the roll of paper, or has the paper wound thereon before it is placed in position in the ends of the brackets H; and to admit of its being readily adjusted and removed from the brackets, the latter are provided with open slots I, over the mouths of which buttons i are arranged to turn and lock or release the ends of the spindle, as may be desired. The ends of the hangers or brackets H extend down into the wax solution in the receptacle E far enough to partially or completely submerge the roll L in the solution. The ends of the brackets h h', &c., extend down to within a short distance of the bottom of the inner tank,

B, the faces of the guide-rolls journaled therein being far enough from the bottom of the tank to allow the paper a free passage without liability of becoming injured by contact with any deposit which may accumulate in the tank. The end *g* of the tank, which projects to a joint a short distance above the bottom of the tank A, has a guide-roller journaled in ears *g*' depending from its corners.

10 The inner tank, B, is also provided with several pairs of brackets, *M m m' m'*, &c., extending from its bottom or from points above its bottom up to the top edges of its sides, or nearly so, and having guide-rollers *N n n' n'*, &c., journaled therein, as shown.

15 The guide-roller *N* might be conveniently journaled in upwardly-extending ears *d* at the top edge of the partition D, and serve to guide the paper or other material over the partition 20 into the compartment C. In passing it from the compartment C over the end of the tank B, I find it convenient to locate a roller on each side of the end of the tank, near its upper edge, and lead the paper over the one on the 25 inside of the tank, and thence through a slit or recess in the end of the tank, thence over the roller on the outside of the end of the tank, and thence downwardly beneath the roller in the end of the cover. Instead of this, I might, 30 however, journal a roller in the upper edge of the tank, as in the case of the roller *N*, and lead the paper over it.

25 The winding-reel O is conveniently journaled in a bracket, P, secured to the end of the cover and adapted to overhang the water in the tank A, outside of the end of the tank B.

30 The rollers *n n' n'*, &c., alternate with the rollers *k k'*, &c., the former being near the top and the latter near the bottom of the tank 40 B. In adjusting the paper within the apparatus the cover G is raised either by purchase or by hand, the roll L is adjusted in the hangers or brackets H, the free end of the paper is then led along over the rollers *N n n'*, &c., and 45 beneath the rollers *k k' k'*, as shown in Fig. 2, and attached to the winding-reel. The cover is then lowered into its position within and on the tank, the rollers *k*, &c., depressing the paper between the rollers *N n n'*, &c., to points 50 near the bottom of the tank, the roll L rotating and giving the necessary length. The paper is thus held in position in manifold open folds throughout the length of the compartment C, and after leaving the compartment C 55 is plunged beneath the surface of the water. A blast of hot air, dry steam, or other gaseous product adapted to volatilize and absorb the solvent in which the wax is dissolved, is admitted to the compartment C through a 60 pipe, Q, preferably provided with a broad mouth, *q*, and is led off at the diagonally-opposite corner of the chamber through an escape pipe, R. The blast thus has access to the paper while the latter is traversing the 65 distances up and down between the rollers *k*, &c., and *N n*, &c., completely volatilizing the solvent and preparing the wax for a sud-

den crystallization when plunged into the cooling-liquid. By means of these folds the paper is exposed to the blast for a maximum 70 length of time in a minimum space, and there is at the same time great economy in heat. Through the escape-pipe R the solvent is led away to a condenser of any well-known or 75 approved construction, where it is collected for reuse, thus effecting a great saving in the cost of manufacture. The tension caused by passing the paper over the many rolls is found to be just what is required to give it the smoothness which is found desirable, and will 80 not, under ordinary circumstances, be liable to tear or pull it apart.

85 In Figs. 4, 5, 6, and 7 the paper is led directly through the blast-chamber, it having been previously more or less heated and dried in the chamber communicating with the wax solution. The cover here rests in a groove in the upper edge of the main tank, excepting where it plunges into the tank of water at the end.

90 By making the blast-chamber or drying-chamber sufficiently long and the groove in the upper edge of the main tank sufficiently deep to enable the water therein to withstand the pressure within the chambers, this device 95 might be effective; but I do not consider it as expedient as that hereinbefore shown.

95 It is evident that other shapes of tanks and arrangements of rollers might be adopted, and that many slight changes might be resorted to 100 in the forms and arrangements of the several parts described without departing from the spirit and scope of my invention; hence I do not wish to limit myself strictly to the construction herein set forth; but,

105 Having fully described my invention, what I claim as new, and desire to secure by Letters Patent, is—

1. In combination, a waxing-chamber, a blast-chamber, a tank of cooling-liquid, and 110 means for moving the material to be waxed continuously through the chambers and the liquid, substantially as set forth.

2. In apparatus for waxing paper and other material, the combination, with a blast-chamber, through which the waxed material is propelled, of a tank of cooling-liquid adapted to receive the waxed material after it leaves the 115 blast, substantially as set forth.

3. In apparatus for waxing paper and other material, the combination, with a blast-chamber for volatilizing the solvent from the wax, of a tank of cooling-liquid adapted to form a portion of the wall of the blast-chamber and means for guiding the waxed material through 125 the cooling-liquid, substantially as set forth.

4. The combination, with the main tank provided with a removable cover, of a waxing-tank and a tank of cooling-liquid separated by a blast-chamber, substantially as set forth. 130

5. The combination, with an inner tank separated into compartments, of a tank of wax in solution located in one of the compartments, a blast-pipe opening into another compartment.

ment, and a tank of cooling-liquid surrounding the sides and ends of the inner tank, substantially as set forth.

6. The combination, with the two-compartment waxing-chamber and the waxed material adapted to pass continuously from a tank of wax solution in one of the compartments through the other compartment and through a cooling-liquid to the winding-reel, of a pipe adapted to furnish an evaporating or volatilizing blast to the second-named compartment and pipes adapted to convey the volatilized solvent from the compartments to a condenser, substantially as set forth.

15 7. A waxing-chamber having a removable cover, the joints between the cover and body being hermetically sealed by a liquid, substantially as set forth.

8. The apparatus, substantially as described, consisting, essentially, of the two-compartment waxing-chamber with its removable cover, the waxing-tank located in one of the compartments, the cooling-tank located without and adjacent to the other compartment, the radiators, the blast-pipe, and the pipe leading from the blast-chamber to a condenser, substantially as set forth.

9. The combination, with the compartment adapted to hold a quantity of wax in solution and the paper or other material to be waxed, leading from said compartment through a blast-chamber to a winding-reel, of guide rollers located at or near opposite walls of the blast-chamber, whereby the paper is caused to 35 pass through the chamber in manifold open folds, substantially as set forth.

10. The combination, with the removable cover provided with a series of guide-rollers secured thereto, of the blast-compartment having a series of guide-rollers attached to its walls, the rollers attached to the cover being arranged to alternate with those attached to the blast-compartment wall, for the purpose substantially as set forth.

11. A removable cover for a waxing apparatus provided with depending roller-hangers and adapted, when lowered into position, to force portions of the material to be waxed toward the bottom of a tank, substantially as set forth.

12. The combination, with the blast-chamber and the guide-rolls adapted to locate the waxed material in open folds within the blast-chamber, of a blast-pipe entering one end of the chamber and a discharge-pipe leading from the opposite end of the chamber, whereby the effect of the blast on the waxed material is prolonged, substantially as set forth.

13. The combination, with a waxing-machine consisting of several hermetically-closed chambers, one containing a tank of wax in solution or liquid state, one provided with a hot evaporating-blast and its accessories, and one with a tank of cooling-liquid, of a series of guiding-rollers so placed in the evaporating-chamber as to compel the material subjected to the process to pass many times backward and forward through the evaporating-chamber in close proximity to the hot blast before it is plunged in the cooling-liquid, substantially as set forth.

14. The waxing apparatus consisting, essentially, of an immersing-chamber, an evaporating-chamber, and a cooling-chamber, a movable cover adapted, when in closed adjustment, to hermetically close the chambers from the outside air, and a system of rollers partly supported from the body and partly from the cover of the apparatus, adapted to adjust a strip of flexible material in a position to and fro several times within the evaporating-chamber, the whole arranged substantially as set forth.

In testimony whereof I have signed this specification in the presence of two subscribing witnesses.

STEPHEN M. CHESTER.
